(57) **CLAIM**

The ornamental design for pill organizer, as shown and described.

DESCRIPTION

FIG. 1 is a front perspective view of pill organizer, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view of its combined state;

FIG. 10 is a rear perspective view of its combined state;

FIG. 11 is an enlarged detail view of area 11 in FIG. 1; and,

FIG. 12 is an enlarged detail view of area 12 in FIG. 1. The dash-dot-dash broken lines in FIGS. 1, 11 and 12 show the boundaries of the enlargements shown in FIGS. 11 and 12, and form no part of the claimed design.
